George Ponarouse
INVENTOR.

UNITED STATES PATENT OFFICE.

GEORGE PONAROUSE, OF SAN FRANCISCO, CALIFORNIA.

NECKTIE-TYING DEVICE.

Application filed June 29, 1922. Serial No. 571,703.

To all whom it may concern:

Be it known that I, GEORGE PONAROUSE, a citizen of the United States, and residing in the city and county of San Francisco, State of California, have invented a new and useful Improvement in Necktie-Tying Devices.

The object of this invention is to construct a practical and simple necktie fastener which can be attached to and detached from the collar with the least exertion, and at the same time insure the wearer against its becoming unfastened or turning lop-sided under any possible neck movement.

15 The following description with the accompanying drawings, is a specification, like letters on the drawings representing like parts.

In the drawings—

20 Fig. 1 is a front view of the necktie fastener.

Fig. 2 is a front view of the necktie fastener with a necktie tied on in four-in-hand style.

25 Fig. 3 is a front view of the fastener, without a necktie, showing its application to a comparatively high turn-down collar and being interlocked with the stud thereof as shown in full lines and in detached position by the dotted lines.

30 Referring to the drawings in detail and as clearly shown in Fig. 1, the device is made of a single strand of spring wire bent into a horizontal shaft A, with sides B and C of about equal height and sloping outwardly; at the top of side C the wire is bent downward, making the arm D, which extends parallel with but some distance below shaft A, and at the lower terminal of this arm a loop E is formed, the loop being adapted to receive the head of a collar button in a manner as will be presently described.

After tying the necktie in four-in-hand style on the fastener, as shown in Fig. 2, 45 the fastener is inserted between the folds of the turn-down collar, as shown in Fig. 3 (the necktie is here eliminated and the outside fold of the collar is partly torn off so as to expose the fastener to view when fastened on the collar button) the tops of the sides B and C are arranged adjacent the juncture of the down-turned portions of the collar, the loop E at the bottom of the collar on the dotted line G G is forced upward 50 obliquely as indicated by dotted line H, till it reaches the button F, where it is snapped on the neck thereof. The pressure of forcing the arm D upward will cause all the parts of the fastener to change a little 55 from their former position, as the dotted lines indicate, but they will relax back to their former position as soon as the loop E is unsnapped from the collar button; the necktie being tied on said fastener will 60 now be held in place until unfastened by unsnapping the loop from the collar button.

Having described my invention, what I claim is:

A fastener of the character described 70 formed from a single strand of wire bent to provide a horizontal portion, converging side pieces rising from the horizontal portion, an arm extending downwardly from one of the side pieces in spaced parallel relation therewith and terminating below the horizontal portion in a loop adapted to receive a collar button as and for the purpose specified.

75 In testimony of which, I hereby affix my 80 signature in the presence of two witnesses.

GEORGE PONAROUSE.

Witnesses:

E. B. STONE,
J. F. BURGIN.
